Des. 1172

Oliver T. Bragg & Michael Burrows,
of St. Louis, Missouri.
Letters Patent No. 1172, Dated Dec. 20, 1859.

The schedule referred to in these Letters Patent and making part of the same,

To all whom it may concern:

Be it known that we Oliver T. Bragg and Michael — Burrows of the City and County of St. Louis and State of Missouri, have invented and produced a new and original design for a print or picture to be used as a trade mark upon a certain manufacture known as 'Bragg's Arctic Liniment' and we do hereby declare that the following is a full clear and exact description of the same reference being had to the annexed drawing thereof and the letters of reference marked thereon.

The design aforesaid is intended to represent a portion of the Arctic region. In the foreground are shown some loose pieces of floating ice A. A. and also some animals (supposed to be natives of that region) resting upon the pieces of loose ice, as seen at (a. b) and besides these there are also a number of men in the foreground of the said picture one of whom is shown at P. resting upon his biceps immediately in front of a Bear C. and just to the right of this Bear C. there is a man wrestling with an other Bear as shown at B. and to the left of the said Bear C. there is another man D. that appears to be running to the assistance of the man fighting the Bear, and carrying with him a bottle of the said Liniment, and still further to the left there is a man E. with a rope in his hand, and two men R with uplifted picks, and just behind the men F and D. there are four other persons seen in a group, doing nothing in particular.

Behind this group of persons there is a mountain of ice, marked A, in front of which a ship, B, and to the right of this ship another mountain of ice is seen marked C, in front of which a ship is seen, an open boat, with two men therein.

To the left of the mountain of ice, H, there is a ship, G, seen in the background, and the back ground represents the Aurora Borealis, that is to say the light reflected from the water and ice towards the sky, over the described picture and making part of it is the words "Bragg's Arctic Liniment" printed or engraved, in the manner shown.

What we claim as our production and desire to secure by letters patent is a picture to be used as a trade mark and designed as described with the words Bragg's Arctic Liniment printed or engraved thereon.
